UNITED STATES PATENT OFFICE.

GEORGE HERBERT BAILEY, OF BROOKLYN, NEW YORK.

FASTENING DEVICE FOR GAME APPARATUS.

No. 817,688.

Specification of Letters Patent.

Patented April 10, 1906.

Application filed February 26, 1904. Serial No. 195,435.

To all whom it may concern:

Be it known that I, GEORGE HERBERT BAILEY, a citizen of the United States, residing at 1371 Putnam avenue, in the county of Kings and State of New York, have invented a new and useful Fastening Device for Game Apparatus to be Known as "Lap-Loop Fastening," of which the following is a specification.

10 My invention relates to improvements in fastening devices for game apparatus, consisting of a supporting device embodying a rigid base-plate and flexible lap-loops; and the object of my improvements is to provide 15 a means whereby all game apparatus designed for parlor use can be firmly fastened to a carpet or the like. I attain these objects as illustrated in the drawings, in which—

Figure 1 is a view of the under side of the 20 supporting device embodying a rigid base-plate A. Fig. 2 is a view of the flexible loop c and lap b and tacks d. Fig. 3 is a view of the supporting device embodying a rigid base-plate A, showing the upper side of the rigid 25 base-plate A with three flexible lap-loops c c c, extending beyond the periphery of the base-

plate A, also showing pins e e e stuck diagonally through the loops c c c.

The flexible loops c, secured to the bottom of the rigid base-plate A by means of tack d, 30 extend beyond the periphery of the base-plate A, and pins e, passing through the loops c outside the periphery of the base-plate A, firmly secures the device to a carpet or the like. 35

What I do claim as my invention, and desire to secure by Letters Patent, is—

A supporting device for game apparatus, embodying a rigid base-plate, flexible loops secured to the bottom of the base-plate and 40 extending beyond the periphery thereof, and pins passing through the loops outside the periphery of the base-plate and adapted to secure the device to a carpet or the like, substantially as described. 45

In testimony whereof I have signed my name to this specification in the presence of two subscribing witnesses.

GEORGE HERBERT BAILEY.
